UNITED STATES PATENT OFFICE.

OTIS HARDIN, OF HUMBLE, AND VEERIN B. DANIELS, OF SOURLAKE, TEXAS.

OIL-WELL STRAINER.

1,202,515.

Specification of Letters Patent.

Patented Oct. 24, 1916.

Application filed March 14, 1916. Serial No. 84,122.

To all whom it may concern:

Be it known that we, OTIS HARDIN and VEERIN B. DANIELS, citizens of the United States, residing, respectively, at Humble and 5 Sourlake, in the counties of Harris and Harding and State of Texas, have invented certain new and useful Improvements in Oil-Well Strainers, of which the following is a specification.

10 This invention relates to strainers for oil and other deep wells and has for its object the provision of a novel construction whereby the inlet surface will be increased; also to provide means whereby the straining member will be protected against injury, 15 and also to provide novel means whereby the several parts will be held in place.

The invention is illustrated in the accompanying drawings and will be herein-after fully described, the novel features being pointed out in the claims following the detailed description.

In the drawings, Figure 1 is an elevation with parts broken away and in section showing our improved strainer applied to an oil well casing; Fig. 2 is a horizontal section on the line 2—2 of Fig. 1; Fig. 3 is a detail longitudinal section; Fig. 4 is a view similar to Fig. 3 showing a different form of strainer wrapping.

In the accompanying drawings, 1 indicates the well casing or pipe which is of any desired diameter and is provided at its ends with threaded portions 2 and 3 adapted 25 to be engaged by couplings 4 and 5 whereby it is connected with the main pipe and with the driving point. Between the threaded extremities longitudinal grooves 6 are formed in the outer surface of the casing 40 and at intervals along the said grooves transverse openings 7 are formed through the wall of the casing so as to admit the liquid thereinto. The external surface of the casing is also provided with a spiral groove 8 45 which extends approximately the full length of the casing and may be of a semicircular form, as shown in Fig. 3, or may be V-shaped as shown at 8' in Fig. 4. The strainer body consists of a wire 9 which is 50 wrapped around the casing and seated in the said spiral groove and of a cross sectional form corresponding to the shape of the groove, Fig. 3 showing a circular cross-section, and Fig. 4 showing a triangular 55 cross-section at 9'. The ends of this wrapping are secured to the casing in any de-

sired practical manner so as to prevent separation of the ends from the casing and the spiral groove will hold the adjacent coils of the wrapping out of contact so that an ample entrance space will be provided to admit the oil or other liquid into the well casing. A protecting jacket 10 is fitted around the casing and the wrapping so as to lie close against the strainer wrapping and thereby hold it firmly in place and also protect it from injury through contact with projecting stones or other substances. This jacket 10 is provided throughout its extent with longitudinal series of openings 11, each of which registers with an opening 7 in the casing 1 and the said openings 11 are larger than the openings 7 so as to provide an ample inlet for the liquid. The ends of the jacket are tapered, as shown at 12, so as to fit against the beveled exterior surfaces of the casing 1, as shown at 13, and are riveted or otherwise secured to the casing. The ends of the couplings 4 and 5 are flared so as to bear upon the tapered ends of the jacket and thereby firmly clamp the same to the casing when the couplings are turned home. If so desired, the openings in the jacket may be in the form of slots, as shown at 14, instead of circular openings 11 and the slots will obviously provide a greater clearance for the liquid so as to prevent choking.

It will be readily noted that our improved strainer provides a construction whereby the strands of the strainer wrapping will be held rigidly and evenly in their proper places and the wrapped surface of the pipe will be perfectly smooth and even throughout the strainer. The ends of the jacket may be swaged or otherwise drawn down to the smooth beveled surface of the casing and will, of course, lie close to the threaded extremities of the casing so that, when the coupling is turned home, the flared end thereof will pass around and over the adjacent end of the jacket and positively protect the same, the jacket protecting the entire strainer wrapping against being scraped off, bruised, or otherwise damaged, as now frequently happens with the ordinary strainer. The jacket also fits snugly against the strainer wrappings so as to hold them in the grooves of the casing.

Our device is very simple and durable and will be found highly efficient in use for the purposes for which it is designed.

Having thus described the invention, what is claimed as new is:

1. The combination of a well casing having inlet openings therethrough and having outwardly beveled portions near its ends, a strainer wrapping fitted upon the said casing and extending over said inlet openings, a jacket fitted over the said wrapping and having its ends secured upon the beveled portions of the casing, said jacket being provided with inlet openings, and couplings fitted to the ends of the casing and having flared ends engaging over the ends of the jacket whereby to aid in holding the jacket to the casing.
2. The combination of a well casing having external longitudinal grooves and openings leading from said grooves to the interior of the casing and provided further

with spaced spiral grooves extending across 20 the longitudinal grooves and the said inlet openings, a spiral strainer wrapping coiled about the casing and having its separate coils embedded in the said spiral grooves, the casing having external outwardly beveled 25 portions adjacent the ends of the wrapping, a jacket fitted closely over the said wrapping and having its ends tapered and secured upon the beveled portions of the casing beyond the ends of the wrapping, and 30 couplings fitted on the ends of the casing and having flared ends bearing upon the tapered ends of the jacket, said jacket being provided with inlet openings.

In testimony whereof we affix our signatures.

OTIS HARDIN. [L.S.]
